UNITED STATES PATENT OFFICE.

MAX PEINLICH, OF WHITE PLAINS, NEW YORK, ASSIGNOR TO MORIS GERINGER, OF YONKERS, NEW YORK, DOING BUSINESS AS GERINGER LIGHTING FIXTURE MFG. CO.

DESIGN FOR A LIGHTING-FIXTURE STRAP OR ANALOGOUS ARTICLE.

Application filed July 22, 1927. Serial No. 22,847. Term of patent 3½ years.

To all whom it may concern:

Be it known that I, MAX PEINLICH, a citizen of the United States, and a resident of White Plains, county of Westchester and State of New York, have invented a new, original, and ornamental Design for a Lighting-Fixture Strap or Analogous Article, of which the following is a specification, reference being had to the accompanying drawing, forming a part hereof.

In these drawings:

Figure 1 is a side elevational view of the lighting-fixture strap or analogous article; and

Figure 2 is a diagrammatic edge view of the same.

I claim:

The ornamental design for a lighting-fixture strap or analogous article substantially as shown.

MAX PEINLICH.
